UNITED STATES PATENT OFFICE.

CHARLES FISCHER, OF NEW YORK, N. Y.

DISPLAY STAND.

Application filed February 20, 1922. Serial No. 537,796.

To all whom it may concern:

Be it known that I, CHARLES FISCHER, a citizen of the United States, residing at 3657 Broadway, city, county, and State of 5 New York, have invented certain new and useful Improvements in Display Stands, of which the following is a specification.

My invention relates to display racks and particularly to a folding two-part display stand which can be quickly and cheaply manufactured, one part being adapted to stand upright and the other forming a more or less inclined shelf, each part being adapted to display either the advertising 10 literature or the article to be displayed.

One of the objects of my invention is to provide such a stand consisting of two wire bails pivoted together, which interlock when the stand is set up and which by merely 20 pressing together the sides of one part can be readily collapsed so as to be folded for shipment.

With the above and other objects in view my invention consists of the parts, improvements and combinations more fully pointed out hereinafter.

Referring to the drawings:

Figure 1 illustrates a front view of the stand when set up in position to display the 30 circulars and article;

Fig. 2 is a side elevation of the parts shown in Fig. 1;

Fig. 3 is a side view of the parts shown in Fig. 2 but with the stand in its collapsed 35 condition as for shipment;

Figs. 4 and 5 are respectively a cross-section and an elevation of a detail showing the ends of the standing bail and the means of connection;

Fig. 6 is a detail of the latching mechanism;

Fig. 7 is a front view of the upright bail;

Fig. 8 is a side elevation of the bail shown in Fig. 7;

Fig. 9 is a front elevation of the bail forming the shelf; and

Fig. 10 is a side elevation of the bail shown in Fig. 9.

The upright bail, which assumes a more 50 or less upright position when the stand is open ready for display, preferably consists of a single piece of wire having uprights or sides 1. Each side is provided with a foot 2 and the bottom of the bail has upturned 55 ends 3.

Means are provided for pivotally connect-

ing the two bails forming the stand. The upright bail is provided with a cross rod 4 connecting the two ends upon which the other bail or shelf is swung.

The shelf bail likewise consists of a single piece of wire provided with eyes 5 at its ends, the said eyes engaging and surrounding the cross rod 4. The cross rod is at the back of the upright and the shelf bail extends between the sides of the upright toward the front, thus providing a rigid and firm stand.

The shelf bail is also preferably provided with a front stop for the article to be displayed. This stop in the form of the invention illustrated, is constituted by a cross wire 6 forming part of the wire bail and uniting its two side arms 7, 8.

Means are provided for latching and interlocking the two bails when the stand is set up and for permitting a ready collapsing of the stand when desired. In the form of the invention illustrated I bend each side of the upright bail so as to provide it with a bent portion forming an ear 9. The shelf bail also has its side arms made resilient and provided with bent portions 10, 11 connected to the side arms by inclined shoulders 10^a, 11^a, the portions 10, 11 forming latches which engage with the ears 9 under the outward spring of the wire arms of the shelf bail. By pressing the side arms of the shelf bail together they will assume the dotted line positions shown in Figs. 1, 6 and 9; the latches will be disengaged from the ears so that the stand may be folded.

The top of the standing bail has its two ends 12, 13 bent so as to form a transverse member and both of the ends are bent again 95 at right angles to the transverse portions at 14. The ends are covered by a clip 15. One of the ends terminates in a hook 16, thus providing means to which a pocket or display device 17 may be secured as shown in 100 dotted lines in Figs. 1 and 2. In this pocket may be carried advertising literature which explains the article carried on the lower shelf. Or the bottom stand can be used to hold circulars or literature and the article 105 may be displayed from the upright stand.

The operation of the invention will be clear from the above description. It will also be understood that changes may be made in the construction of the parts without departing from the principle of the invention.

What I claim and desire to secure by Letters Patent is:

1. A folding, two-part display stand comprising a pair of wire bails pivotally connected, one adapted to stand upright and the other inclined, the upright bail forming a display member upon which may be supported advertising matter and the inclined bail forming a shelf to receive an article to be displayed, each of the sides of said upright bail being provided with an ear with which ears the arms of the shelf are adapted to engage, so as to latch the members in displaying position and to disengage so as to unlatch the members when folding the same.

2. A folding display stand having in combination a wire frame provided with an ear at the bottom of the side of the frame and a swinging wire shelf pivoted to said frame and carrying a latch adapted to engage the said ear, so as to interlock the frame and shelf, when the stand is open.

3. A folding display stand having in combination a frame provided with feet, the sides of the frame being bent to form ears, and a shelf pivoted to said frame, the sides of the shelf having an outward spring and being adapted to engage the said ears so as to interlock therewith when the stand is open.

4. A folding, two-part display stand comprising a pair of wire bails pivotally connected, one adapted to stand upright and the other inclined, the upright bail forming a display member upon which may be supported advertising matter and the inclined bail forming a shelf to receive an article to be displayed, said inclined bail also provided with a front stop for the article, said upright bail provided with a pair of ears with which the arms of the shelf are adapted to engage, so as to latch the parts in displaying position.

5. A folding, two-part display stand comprising a pair of wire bails pivotally connected, one adapted to stand upright and the other inclined, the upright bail having at its top a hook upon which may be supported advertising matter and the inclined bail forming a shelf to receive an article to be displayed, said inclined bail provided with a crosswire forming a front stop for the article, said upright bail provided with a pair of ears with which the arms of the shelf are adapted to engage, so as to latch the parts in displaying position.

6. A folding display frame having in combination a pair of wire bails pivotally connected, one bail adapted to stand upright and consisting of a single piece of wire, the said wire being bent so as to provide two sides, each side having a bent portion forming an ear, located toward the bottom of the side, each side having a foot, the said bail having upturned ends connected by a cross

rod, the other bail forming a shelf and consisting of a single piece of wire provided with eyes at its ends, the said eyes engaging the said cross rod and the sides of the shelf being adapted to engage the ears of the upright.

7. A folding display frame having in combination a pair of wire bails pivotally connected, one bail adapted to stand upright and consisting of a single piece of wire, the said wire being bent so as to provide two sides, each side having a bent portion forming an ear, located toward the bottom of the side, each side having a foot, the said bail having upturned ends connected by a cross rod, the top of the bail consisting of a transverse portion, the other bail forming a shelf and consisting of a single piece of wire provided with eyes at its ends and having two side arms, each arm provided with a bent portion forming a latch, the said eyes engaging the said cross rod and the said latches adapted to engage the ears of the upright.

8. A folding display frame having in combination a pair of wire bails pivotally connected, one bail adapted to stand upright and consisting of a single piece of wire, the said wire being bent so as to provide two sides each side having a bent portion forming an ear, located toward the bottom of the side, each side having a foot, the said bail having upturned ends connected by a cross rod, the top of the bail consisting of its two ends bent transversely and again at right angles to the transverse portions, both ends being covered by a clip and one of the ends being bent to form a hook, the other bail forming a shelf and consisting of a single piece of wire provided with eyes at its ends and having two side arms, each arm provided with a bent portion forming a latch, the said eyes engaging the said cross rod and the said latches adapted to engage the ears of the upright, the side arms of the shelf being connected by a cross wire forming a front stop.

9. A folding display frame having in combination a pair of wire bails pivotally connected, one bail adapted to stand upright and consisting of a single piece of wire, the said wire being bent so as to provide two sides, each side having a bent portion forming an ear, located toward the bottom of the side, each side having a foot, the said bail having upturned ends, the other bail forming a shelf, means for pivotally mounting said shelf upon said upturned ends, the arms of the shelf passing between the sides of the upright when the stand is open, said arms being resilient and provided with portions engaging the ears of the upright bail to interlock the two frames.

In testimony whereof, I have signed my name to this specification.

CHAS. FISCHER.
